UNITED STATES PATENT OFFICE.

MATILDA A. HILL, OF SOUTH FALLSBURG, NEW YORK.

DESIGN FOR A HANDLE FOR BUTTONERS.

SPECIFICATION forming part of Design No. 36,074, dated September 16, 1902.

Application filed June 22, 1901. Serial No. 65,701. Term of patent 3½ years.

To all whom it may concern:

Be it known that I, MATILDA A. HILL, a citizen of the United States, residing at South Fallsburg, in the county of Sullivan and State of New York, have invented and produced a new, original, and ornamental Design for a Handle for Buttoners, of which the following is a specification, reference being had to the accompanying drawing, forming part thereof.

10 The drawing shows a plan view of a buttoner embodying my new design.

As shown in the drawing, the leading or material feature of my design consists of a handle portion 6, which is transversely elliptical and in plan is substantially oval. Each side face of the handle is ornamented with a

spray of flowers. The spray includes a stem which winds from one side to the other of the handle and at the lower portion has leaves which are curled to extend transversely of 20 the handle, the upper portion of the spray having a flower at both sides of which are represented buds.

Having described my invention, what I claim as new, and desire to secure by Letters 25 Patent, is—

The ornamental design for a handle for buttoners, as herein shown and described.

MATILDA A. HILL.
